UNITED STATES PATENT OFFICE.

JOHN GSCHWIND AND CHARLES GSCHWIND, OF NEW YORK, N. Y.

IMPROVEMENT IN CAR-REGISTERS.

Specification forming part of Letters Patent No. 59,387, dated November 6, 1866.

To all whom it may concern:

Be it known that we, JOHN GSCHWIND and CHARLES GSCHWIND, of the city, county, and State of New York, have invented a new and Improved Passenger-Register for Railroad-Cars and other Public Conveyances; and we do hereby declare that the following is a full, clear, and exact description thereof, which will enable others skilled in the art to make and use the same, reference being had to the accompanying drawings, in which—

Figure 1 is an end view of a car with our invention applied to it; Fig. 2, an inverted plan of the same, partly in section.

Similar letters of reference indicate like parts.

This invention relates to a new and improved register for street-railroad cars and other public conveyances, for the purpose of indicating the number of passengers carried during a trip, thereby serving as a check for dishonest conductors and employés.

The invention consists in conferring the ingress to one passage only, and having in said passage an upright shaft provided with lateral arms, like a turnstile, so that a person in entering a car or passing on a ferry-bridge will necessarily turn the shaft, and in so doing communicate motion, through the medium of suitable gearing, to an index working over a dial, as hereinafter fully shown and described.

In the following description the invention refers to the application of the invention to a street-railroad car.

A represents one end of a railroad-car, B being the platform; and C is an upright shaft, which may be close to the end of the body of the car, and protected by a casing, D. The upper end of this shaft C has four horizontal arms, a, attached to it, which extend across the platform B, just above the rail or guard E at its end, and near the step a' at one side of the platform, so that a person in entering the car

will necessarily turn the shaft C one-quarter of a revolution in the direction indicated by arrow 1.

The shaft C is prevented from turning in the opposite direction by means of a ratchet, b, on its lower end, into which a pawl, c, catches. (See Fig. 2.)

At the opposite side of the platform B there is a shaft, F, also provided with horizontal arms d, like the shaft C, and having a ratchet, e, on its lower end, with a pawl, f, catching into it, the teeth of the ratchet e being in a reverse position to those of the ratchet b, in order to admit of the arms d turning outward, as indicated by the arrows 2, to allow passengers to pass out, the arm d not being allowed to turn in the opposite direction to admit passengers in at that side of the platform.

The shaft C, connected underneath the body of the car by gearing g with a shaft, h, which extends upward within a seat of one side of the car, and has an index, i, upon it, which works over a dial, i*. This index and dial records or indicates the turns of the shaft C, and consequently the number of passengers that have entered the car.

The arrangement is extremely simple and efficient, and may be applied at a moderate cost, and will operate perfectly.

Having thus described our invention, we claim as new and desire to secure by Letters Patent—

The combination and arrangement of the shaft C, arms a, ratchet b, pawl i, gearing g, shaft h, index i, and dial i* with the car A, which is provided with the egress-armed shaft F on the opposite side, as and for the purpose specified.

JOHN GSCHWIND.
CHARLES GSCHWIND.
